ULRICH BARSKE, OF HANOVER-RICKLINGEN, GERMANY, ASSIGNOR TO HANNOVERSCHÉ MASCHINENBAU-ACTIENGESELLSCHAFT, VORMALS GEORG EGESTORFF, OF HANOVER-LINDEN, GERMANY

WATER BOILER PARTICULARLY FOR LOCOMOTIVES AND LOCOMOBILES

Application filed December 4, 1929, Serial No. 411,546, and in Germany May 26, 1928.

In locomotive- and water-tube boilers it is known to fit the space forming the boiler barrel and the firebox with straight inclined water tubes.

5 This invention has for its object, to construct this type of boiler, in which the best imaginable efficiency is obtained with the smallest space requirement, so that it can be cleaned and maintained in the simplest 10 manner and can be changed over without special alterations for working with one or more pressure stages, with or without superheating or in any other suitable manner.

This is attained in that the absolutely 15 straight inclined tubes forming the boiler are fixed stationary but easily removable at one end and mounted individually axially shiftable at the other end, the connection to the water- and steam-collecting chambers respectively is effected by separate connecting tubes, the connection of which is obtained by lens-shaped packings or equivalent means. The 20 position of the individual inclined tubes, which, for the purpose of facilitating the manufacture and storing, are preferably of 25 the same diameter, irrespectively whether they are to conduct water, steam or a water-steam mixture, is ensured by loosely guiding the tubes at one end in suitable bores in the 30 rear wall of the firebox, and mounting the same at the other end in vertical or horizontal rows on the smoke box or in bars which are grooved, so that the tubes extending through the gaps formed between two bars 35 can easily be exchanged. This makes it also possible for the heating gases, to pass through without encountering considerable resistance.

In order to be able to easily exchange the 40 inclined tubes, the ends of the tubes on the wall of the firebox are constructed so that they can be drawn through holes in the rear wall of the firebox together with the elements, for example flanges, necessary for the packed 45 connection with the connecting tubes. The inclined tubes are steamtight connected on the smokebox bars with the connecting tubes in such a manner, that the packing parts hold at the same time stationary one or both tubes 50 on the bar. As the connecting tubes are only

of small diameter, the inclined tubes can also be considerably reduced at both ends thereby enabling the width of the bars to be kept as small as possible, and the parts necessary for establishing the steamtight connection are made of such small diameter that the tubes can be pulled through the gaps between the fastening bars.

55 By these arrangements it is possible, to also render all or individual inclined tubes available for other purposes than for water evaporation, for example for the superheating of steam in the first or second stage or the like, in that the inclined tubes are connected with other collectors merely by reversing the connecting tubes. Thus individual tubes can be used solely for heating purposes, for example in cold weather.

60 Several embodiments of the invention are illustrated by way of example in the accompanying drawing in which:

65 Fig. 1 shows a longitudinal section of a locomotive boiler.

70 Fig. 2 is a cross-section through the smokebox,

75 Fig. 3 shows a cross-section through the inclined tube boiler.

80 Fig. 4 is a cross-section through the firebox,

85 Figs. 5 and 6 are longitudinal sections showing two forms of construction of the fitting of the inclined tubes, their fastening on the bars and the connection with the connecting tubes.

90 The boiler is formed of inclined tubes 1, which extend through the available space from the rear wall 2 of the firebox 4 to the smokebox 3, whereas the side walls of the firebox 4 are covered in longitudinal direction with similar but correspondingly shorter tubes 5. For the purpose of conducting the heating gases the tubes are enclosed by a jacket 6, the inside of which is preferably covered with a heat protecting substance, such as chamotte 7, asbestos or the like. The inclined tubes 1 and 5 are absolutely straight and fastened, easily detachable, in the manner which will be hereinafter described, onto or in bars 8 on the smokebox, whereas the tubes on the side of the firebox loosely pro- 95

ject singly through holes 9 in the rear wall of the firebox. The connection of the inclined tubes with the water- and steam-collecting chambers 10 and 11 respectively is effected by separate connecting tubes 12 and 13 respectively so that the tubes may be easily interchanged. It is immaterial for the invention, in which manner the circulation of the boiler water is closed; preferably however 10 a top drum will be used as illustrated in Figs. 1 and 4.

As shown in Figs. 5 and 6 the packing connection of the inclined tubes with the connecting tubes is effected by lens-shaped packings 14. In order to enable pulling out of the tubes through the holes in the rear wall 15 of the firebox for interchanging, tubes are used, according to the invention, the ends of which are reduced to such a diameter that 20 their packing flanges 15 can be drawn through the bores 9 in the firebox wall. The inclined tubes on the smokebox are likewise connected to the connecting tubes 13 by lens-shaped packings 14, the flanges 16 or 17 necessary for obtaining the tight connection serving at the same time to give a stationary bearing to one or both tubes as shown by the fixing bolts 18 and 19 respectively. In order to be able to exchange the inclined tubes leading 30 to the smokebox, the bars 8, to which the horizontal or vertical rows of inclined tubes are fastened, are made as thin as possible, so as to allow of the passing of the tubes through the gaps between every two bars. For this 35 purpose the ends of the inclined tubes are reduced towards the smokebox to the smallest size permissible which just allows the tight connection with the connecting tubes 13. Further, as shown in Fig. 2, each bar is cut 40 out on both sides as far as possible so that further gaps 20 are formed between every two juxtaposed bars, through which gaps the inclined tubes can be interchanged after 45 the packing connection has been loosened. According to the kind of firing and the construction smoke deflecting walls 21 may, if necessary, be arranged at a suitable point between the tubes, as shown for example in Fig. 50 1, or the inclined tubes may be inclined in the opposite direction so that their highest point lies near the hottest zone, and the fire gases flow in counter direction to the water circulation.

55 I claim:—

1. A water tube boiler particularly for locomotives and locomobiles comprising a set of inclined straight tubes for conducting water, steam or a water-steam mixture extending through the space forming the smoke box and the upper part of the firebox, similar shorter tubes arranged on the side walls of the firebox, a detachable connecting tube for 60 each end of the inclined tubes, and collector 65

chambers to which with said inclined tubes are connected by said connecting tubes.

2. A water-tube boiler as specified in claim 1, comprising in combination with the inclined tubes, bars in said smoke box in which 70 said inclined tubes are mounted in rows, a packing connection between the rear connecting tubes and said inclined tubes adapted to hold one or both tubes stationary on said bars.

3. A water tube boiler as specified in claim 75 1, in which the inclined tubes have reduced ends to facilitate connection with the carrying bars and juxtaposed to each other, said bars being cut out on the two sides to provide spaces through which said inclined tubes 80 can be removed.

4. A water tube boiler as specified in claim 85 1, comprising in combination with the inclined tubes having reduced ends the said connecting tubes being of smaller diameter than the inclined tubes, a firebox having bores in the rear wall through which said inclined tubes are loosely inserted, and flanges on the ends of said inclined tubes serving as packing means for the connection with said connecting 90 tubes and adapted to be passed through said bores.

In testimony whereof I affix my signature.
ULRICH BARSKE.
